UNITED STATES PATENT OFFICE.

FRANZ HOENIG, OF NEW YORK, N. Y., ASSIGNOR TO TOBLER & HOENIG, OF NEW YORK, N. Y., A FIRM COMPOSED OF WILLIAM A. TOBLER, FRANZ HOENIG, AND WALTER R. TOBLER.

DESIGN FOR EMBROIDERY.

57,474.

Specification for Design.

Patented Apr. 5, 1921.

Application filed January 7, 1921. Serial No. 435,747. Term of patent 3½ years.

To all whom it may concern:

Be it known that I, FRANZ HOENIG, a citizen of Switzerland, residing at New York, in the county of New York and State of New York, have invented a certain new, original, and ornamental Design for Embroidery, of which the following is a specification.

Said design consists in an embroidery pattern, as illustrated in the accompanying drawing, wherein the figure is a portion of a piece of embroidery showing my new design. The design repeats indefinitely on the fabric in accordance with the length of the piece of embroidery.

What I claim as new is:

The ornamental design for embroidery as herein shown and described.

In witness whereof, I have hereunto set my hand and seal at New York, New York, this 20th day of December, A. D. nineteen hundred and twenty.

FRANZ HOENIG. [L.S.]
